UNITED STATES PATENT OFFICE.

JAMES F. SCOTT AND ROBERT F. SCOTT, OF NEW YORK, N. Y.

INTERNAL-COMBUSTION ENGINE.

1,256,382.

Specification of Letters Patent. Patented Feb. 12, 1918.

Application filed February 19, 1917. Serial No. 149,495.

To all whom it may concern:

Be it known that we, JAMES F. SCOTT and ROBERT F. SCOTT, citizens of the United States, and residents of the city of New York, borough of Manhattan, in the county and State of New York, have invented a new and Improved Internal-Combustion Engine, of which the following is a full, clear, and exact description.

10 This invention relates to improved means for translating longitudinal force into a rotary force and particularly to an improved internal combustion engine which converts directly the explosion of an explosive matter into rotary motion.

The object in view is to provide an improved construction of engine whereby successive explosions may be converted into a rotary motion with the use of a minimum 20 number of parts.

Another object in view is to provide an internal combustion engine formed with a reciprocating member and means for rotating the same during its reciprocatory 25 movement in order that the impulse caused by the explosion of an explosive matter will be translated into rotary motion in such manner as to utilize substantially all of the energy in producing the rotary motion and also take advantage of the influence of centrifugal force.

In the accompanying drawings:

Figure 1 is a longitudinal vertical section through an engine disclosing one embodiment of the invention.

Fig. 2 is a view similar to Fig. 1 with certain parts shown in elevation and immediately before the explosion, the parts being shown on a reduced scale.

40 Fig. 3 is a sectional view through Fig. 2 on line 3-3.

Fig. 4 is a transverse sectional view through Fig. 2 on line 4-4.

Fig. 5 is a diagram showing the arrangement of guiding grooves used in adapting the moving parts to the 4-cycle principle.

Referring to the accompanying drawings by numerals, 1 indicates a casing of any desired kind provided with end members 2 and 3, end member 2 being formed with chambers 4 and 5 acting as inlet and exhaust chambers. An intake pipe 6 is provided which is connected with chamber 4, while an outlet pipe 7 is provided for directing the exhaust to a convenient point. The casing 1 is supported on any suitable

foundation and is held against movement in case the shaft 8 is to be rotated, but it is evident that if the desired shaft 8 could be held fixed and the casing 1 rotated without 60 in any way departing from the spirit of the invention or changing the principles involved.

As shown in Fig. 1, the shaft 8 extends through the casing 1 and is supported 65 therein by suitable bearings 9, which bearings may be of the ordinary antifriction type as shown in Fig. 1, or may be thrust bearings, if desired, usually some form of thrust bearing being provided to prevent 70 excessive friction between the walls of chamber 10 and the inner plate 11 of end 2. The chamber 10 is formed integrally with shaft 8 or is rigidly secured thereto and has rigidly connected therewith the bellows 12 and 75 13, which bellows form the combustion chamber. The opposite ends of the bellows 12 and 13 are connected in any suitable way, as for instance, by being screwed or welded to what may be termed a piston 14 which is 80 slidably mounted on shaft 8 but splined thereto by a suitable key 15 so that the piston must rotate with the shaft. The detail construction of the chamber produced by the bellows structure 12-13 and associated 85 parts will not be described as it is identical with the structure disclosed in the patent to James F. Scott, issued April 22, 1916, No. 1,180,947 and the allowed application of James F. Scott, No. 102,631 filed June 9, 90 1916.

The ends of each of the bellows 12 and 13 are connected to the walls of chamber 10 and to one of the walls of the piston 14 so that the movement caused by the explosion of an explosive mixture in the chambers will be translated to a longitudinal movement of the piston 14, which longitudinal movement will be translated by a 95 system of grooves 16 and 17 and balls 18 into a rotary movement. The piston 14 by reason of these grooves and balls rotates 100 upon its back and forth movement while sliding along the shaft 8 guided by the key 15. The grooves 16 and 17, as shown in the diagram in Fig. 5, are formed so that it will require four longitudinal movements of piston 14 to produce one rotary movement, whereby the entire construction is 105 adapted to the 4-cycle principle of explosive engines.

For instance, upon the explosion the parts

will move from the position shown in Fig. 2 to the position shown in Fig. 1 under the influence of the power produced by the expanding gases, and from the position shown in Fig. 4 the bellows will move back to their former position, and as the piston 14 moves back it will rotate for a quarter of a revolution, this backward movement of the bellows acting as an exhaust stroke. The next forward movement of the parts will cause the bellows to draw in a new charge of explosive mixture and at the same time rotate the piston 14 a quarter of a revolution. Upon the return movement of the piston 14 after the intake stroke the piston will rotate a quarter of a revolution and the collapsing of the bellows will compress the gases to the desired extent ready for the next explosion. As shown in the drawings, the balls 18 have been provided in suitable adjustable plugs 19, but it is evident that other means may be provided as well as the balls or as a substitute for the balls without departing from the spirit of the invention. For instance, the plug 19 could be reduced and rounded at the end so as to act in the grooves though the free movement of the balls is preferable.

The intake and exhaust openings are arranged in the end 2 as shown in Fig. 3, the exhaust opening 20 being preferably larger than the intake opening 21 so as to give more time for the expulsion of the burnt gases. These openings may be set at any suitable distance apart for producing the results desired, and by reason of the fact that the plug 22 is stationary and has only one contact while the opposite contact is connected with the walls of the casing 1 no timing mechanism is necessary, as upon each rotation of the chamber 10 the contact or plug 22 will come opposite the contact 23, whereupon a spark will be produced.

What we claim is:

1. An internal combustion engine comprising a combustion chamber formed with collapsible sections whereby when an explosion occurs in said chamber one end of the chamber will be moved a predetermined distance from the opposite end, a power member connected to the movable end of said chamber, means acting on said power member for causing the same to rotate as it is moved by said combustion chamber, and a rotatable shaft slidably connected with said power member whereby the shaft is rotated by the power member during its movement.

2. An internal combustion engine comprising a collapsible power chamber, a rotatable power member connected with said power chamber and reciprocated thereby, means acting on said power chamber for causing the same to rotate as it is reciprocated, a shaft extending through said

tary power member, and means for connecting said rotary power member with said shaft whereby the shaft is rotated.

3. An internal combustion engine, comprising a rotatable shaft, means for supporting said shaft, an explosive chamber connected with said shaft at one end and designed to expand longitudinally of the shaft, a rotary power member connected with said chamber and adapted to be moved longitudinally of the shaft with the chamber, means slidably connecting said shaft with said power member, and means engaging said power member for causing the same to rotate as it reciprocates.

4. In an internal combustion engine, a power shaft, an intake chamber connected with said shaft, a combustion chamber formed of collapsing sections connected with said chamber and arranged to be continually in free communication therewith, means for producing an explosion in said chamber so as to cause one end of the collapsing sections to move longitudinally of said shaft, a power member connected with said collapsing sections and moved thereby, a spline for connecting said power member with said shaft, and means acting on said power member for causing the same to rotate as it is moved longitudinally of the shaft.

5. In an internal combustion engine of the character described, a collapsible explosion chamber, a reciprocating power member, means acting on the power member for causing the same to rotate during the reciprocation thereof, a shaft extending through said power member, and a spline for slidably connecting the power member with the shaft whereby said shaft is rotated.

6. An internal combustion engine comprising a rotatable shaft, a cylinder formed with expanding parts rigidly connected with said shaft and arranged so that one end will move back and forth along the shaft, a power member connected to said movable end, fixed means connected with said power member for causing the same to rotate when reciprocated by said cylinder, and means for connecting the power member with said shaft for rotating the shaft.

7. An internal combustion engine, comprising a casing having an end provided with an exhaust opening and an intake opening, a shaft extending through said casing, a gas chamber rigidly connected with said shaft arranged adjacent said end and formed with a single opening adapted to pass successively the exhaust from said intake openings, a power element connected with said gas chamber, a reciprocating element connected with said power member and actuated thereby, means acting on said reciprocating element for causing the same to rotate, means connecting said reciprocating element and said shaft whereby said

shaft is rotated and the gas chamber connected thereto, and a sparking mechanism with one contact carried by the gas chamber and the other by said end, said contacts being arranged to cause a spark once for each revolution of the gas chamber.

8. An internal combustion engine, comprising a casing formed with an end having an inlet and exhaust opening, a gas chamber rotatably mounted adjacent said end and formed with a single opening adapted to register successively with the openings in said end, a power chamber connected with said gas chamber and rotatable therewith, means for producing a spark in said gas chamber once for each revolution thereof, a power shaft, and means for translating movement from said power chamber to said shaft for rotating the same.
9. An internal combustion engine, comprising a pair of nested collapsible bellows forming an explosion chamber therebetween, the inner bellows having an opening extending therethrough, a power shaft extending through said opening, means for connecting one end of each of said bellows to said power shaft so that the bellows will rotate with the power shaft, a reciprocating element connected to the opposite ends of each of said bellows, means for causing said reciprocating element to rotate as it reciprocates, and means for connecting said reciprocating element with said shaft for transmitting power to the shaft for rotating the same.

10. An internal combustion engine, com-

prising a power element formed with an inner and an outer set of collapsible sections, the space between said sections forming a combustion chamber, a reciprocating element connected to said power element, means acting on the reciprocating element for causing the reciprocating element to rotate as it reciprocates, and means for transmitting power from said reciprocating element to a rotary member.

11. An internal combustion engine, comprising a combustion chamber formed by collapsible sections whereby when an explosion occurs in said chamber one end of the chamber will be moved a predetermined distance from the opposite end, a power member connected to the movable end of said chamber, means acting on said power member for causing same to rotate as it is moved by said chamber and means for transmitting power from said power member to a rotary member.

12. An internal combustion engine, comprising a combustion chamber formed with collapsible sections whereby when an explosion occurs in said chamber one end of the chamber will be moved a predetermined distance from the opposite end, a power member connected to the movable end of said chamber for transmitting power therefrom, and means acting on said power member for causing the same to rotate as it is moved by said combustion chamber.
